[57] CLAIM

The ornamental design for a combined caddy for personal accessories with bin and tray elements, as shown and described.

DESCRIPTION

FIG. 1 is a perspective view of the combined caddy for personal accessories with bin and tray elements showing our new design;

FIG. 2 is a front elevational view of the caddy of FIG. 1, the rear elevational view being a mirror image thereof;

FIG. 3 is a side elevational view of the caddy of FIGS. 1 and 2, the opposite side elevation being a mirror image thereof;

FIG. 4 is a top plan view of the caddy of FIGS. 1 to 3;

FIG. 5 is a bottom plan view of the caddy of FIGS. 1 to 4;

FIG. 6 is a perspective view of a tray element of the caddy of FIGS. 1 to 5;

FIG. 7 is a front elevational view of the caddy tray element of FIG. 6, the rear elevational view being a mirror image thereof;

FIG. 8 is a side elevational view of the caddy tray element of FIGS. 6 and 7, the opposite side elevation being a mirror image thereof;

FIG. 9 is a top plan view of the caddy tray element of FIGS. 6 to 8;

FIG. 10 is a bottom plan view of the caddy tray element of FIGS. 6 to 9;

FIG. 11 is a perspective view of a bin element of the caddy of FIGS. 1 to 5;

FIG. 12 is a front elevational view of the caddy bin element of FIG. 11, the rear elevational view being a mirror image thereof;

FIG. 13 is a side elevational view of the caddy bin element of FIGS. 11 and 12, the opposite side elevation being a mirror image thereof;

FIG. 14 is a top plan view of the caddy bin element of FIGS. 11 to 13; and,

FIG. 15 is a bottom plan view of the caddy bin element of FIGS. 11 to 14.
